DESIGN FOR A STAPLING MACHINE

Stephen A. Crosby, New York, N. Y., assignor to Parrot Speed Fastener Corporation, Long
Island City, N. Y., a corporation of New York

Application April 26, 1937, Serial No. 68,990

Term of patent 14 years

To all whom it may concern:

Be it known that I, Stephen A. Crosby, a citizen of the United States, residing in Manhattan, in the city, county, and State of New York, have invented a new, original, and ornamental Design for Stapling Machines, of which the following is a specification, reference being had to the accompanying drawing, forming a part thereof in which:—

Fig. 1 is a side elevational view of a stapling machine showing my new design.

Fig. 2 is a plan view of Fig. 1 and
Fig. 3 is a front view of Fig. 1.

The essential feature of my invention resides in the split arm comprising a magazine and a swingable superimposed cover having a downwardly and rearwardly curved top face.

I claim:—

The ornamental design for a stapling machine, substantially as shown and described.

STEPHEN A. CROSBY.
